UNITED STATES PATENT OFFICE.

ISAAC WATKINS, OF HARTFORD, CONNECTICUT.

BURGLAR-ALARM.

No. 823,831.

Specification of Letters Patent.

Patented June 19, 1906.

Application filed July 12, 1905. Serial No. 269,316.

To all whom it may concern:

Be it known that I, ISAAC WATKINS, a citizen of the United States, and a resident of Hartford, in the county of Hartford, and 5 State of Connecticut, have invented and produced a new and Improved Burglar-Alarm, of which the following is a specification.

My invention relates to that class of devices which are attached to or in connection 10 with a window or door and which are operated on opening of the window or door to sound an alarm; and the object of my invention is to provide a device in which a single alarm may serve for a plural number of windows or doors; and a further object of the invention is to provide a device that may be applied to structures of different dimensions; and a further object of the invention is to provide a device that, while certainly indicating 15 by sounding of the alarm the movement of a window or door to open the same, shall allow the door or window to be closed without sounding the alarm. One form of device in the use of which these objects may be attained is illustrated in the accompanying drawings, in which—

Figure 1 is a view, partially diagrammatic, showing in elevation a part of two window frames and sashes provided with my improved attachment. Fig. 2 is a detail view showing a modified form of the trip-lever. Fig. 3 is a detail plan view of the trip-plate-supporting arm. Fig. 4 is a diagrammatic view illustrating the application of my invention employing a number of sounding devices for a single gong. Fig. 5 is a detail view showing the slot in the pawl.

In the accompanying drawings the numeral 1 denotes a portion of a window-frame, 40 and 2 a sash to which my attachment is applied. A trip-plate 3 is attached to the window-sash by means of an adjustable connection including a base 4, which is secured to the sash, having a socket 5. An arm 6 is adjustably secured to this socket, a clamp-screw 7 being employed to lock the arm in any desired position. This arm 6 is of angular shape, as shown in Fig. 3, and has secured thereon a socket-piece 8, to which the trip- 45 plate 3 is secured. It will thus be seen that the trip-plate support is a sectional structure consisting of the socket-pieces 5 and 8 and the arm 6. The socket-piece 8 may be clamped on the arm 6 in any desired position 50 by means of the clamp-screw 9. A trip-le-

ver 10 is mounted on a pivot 11 on the window-frame, this trip-lever bearing a pawl 12 on the end adapted to engage trips 13 on the trip-plate 3. These trips may be arranged with any desired interval between them and 60 in any desired number. A stop 14 limits the downward movement of the trip-lever 10, the pawl 12 being located normally in the path of movement of the trips 13. This pawl has a socket for the reception of the 65 trip-lever 10, on which it has a sliding movement, a spring 15 holding the pawl normally at the outer limit of its play. An angularly-shaped slot 16 is located in the pawl, in which a pin 17 from the trip-lever is located. The 70 pawl is inserted in place by moving it endwise, the pin 17 passing along the slot to the inner portion thereof located at one side of the mouth of the slot. When it is desired to disconnect the alarm, the pawl may be moved 75 back and turned, locating the pin in the angular portion of the inner end of the slot.

In the modified form of the device shown in Fig. 2 the trip-lever 18 has a swinging pawl 19 on its outer end. This pawl has a 80 ledge 20 engaging with a stop 21 to prevent upward movement of the outer end of the pawl and compel the lever to move upward with the pawl. This pawl yields, however, to allow the trips 13 to pass in a downward 85 movement of the sash, and a spring 22 returns the pawl to its normal position.

The trip-lever 10 is connected, as by means of a cord or other flexible connection 23, with a striker 24. As shown in Fig. 1, flexible connections from a number of trip-levers may be attached to a single striker 24. This striker is pivoted in proximity to a gong 25 and is pulled toward the gong, as by means of a spring 26. 95

In the operation of the device as the window is raised the trip 13, engaging the pawl on one of the levers 10, pulls on the connection 23, drawing the striker away from the gong. When the sash has been raised sufficiently, the pawl slips from the trip and the spring 26 draws the striker against the gong, sounding an alarm. 100

In Fig. 4 of the drawings a single gong 27 is employed, around which are located a 105 number of striker-arms 28. These are operated in a manner similar to the striker-arm shown in Fig. 1, and it is obvious that the pull on the cords 29 may be obtained in the same manner as shown in Fig. 1 or in any 110

other desired manner. An indicator 30 is located appurtenant to each of the levers 28, this indicator consisting of a case 31, in which is located a slide 32, having a stem 33 lying in the path of movement of the arm 28. The slide 32 bears a number corresponding to the room from which a connection to the lever appurtenant to this slide extends, and this slide normally rests within the case, as shown at the upper part of Fig. 4. If a window shall be raised in a room, the movement of the lever 28 to sound the alarm strikes the stem 33, moving the plate outward, as shown at the striker-arm located at the lower part of Fig. 4.

From the above description, taken in connection with the drawings, it will be seen that my improved device may be readily attached to any window without regard to the thickness of the window-frame or the width of the sash, the parts being readily adjusted to accommodate windows or frames of different dimensions.

What I claim as my invention, and desire to secure by Letters Patent, is—

1. An alarm, a striker appurtenant thereto, a trip-plate provided with means of attachment to a movable part and bearing trips, a trip-lever interposed in the path of movement of the trip-plate and having a pawl to compel movement of the lever in the movement of the trip-plate in one direction but yielding to allow movement of the trip-plate in the opposite direction, and a lengthwise-movable connection between the trip-lever and striker.

2. A trip-plate bearing a number of trips and arranged to be secured to a movable part, a trip-lever bearing a pawl compelling movement of the lever in one direction of movement of the trip-plate, but yielding to allow it to pass in a movement in the opposite direction, a gong with a striker appurtenant thereto, and means on said striker for direct attachment of lengthwise-movable connections with a plural number of trip-levers.

3. In an alarm device, a base with means of attachment to a movable part and having a socket-piece, an arm adjustably mounted in the socket-piece, a trip-plate borne by said arm and having a trip, a trip-lever having a pawl located in the path of movement of said trip, said pawl yielding to permit movement of the trip in one direction but unyielding in the movement of the trip in the opposite direction, a gong, a striker therefor, and connections between said striker and trip-lever.

4. In an alarm device, a base having means for attachment to a movable part, an arm supported by the base, a trip plate having a socket-piece adjustably mounted on said arm and bearing a trip, a trip-lever having a pawl located in the path of movement of said trip and yielding to allow movement of the trip in one direction but unyielding in the

movement of the trip in the opposite direction, a gong, a striker therefor, and connections between said striker and trip-lever.

5. In an alarm device, a base provided with attachment to a movable part and having a socket-piece, an arm adjustably mounted in said socket-piece, a trip-plate having a socket-piece adjustably mounted on said arm and bearing a trip, a trip-lever having a pawl located in the path of movement of said trip and yielding in the movement of the trip in one direction but unyielding in its movement in the opposite direction, an alarm, a striker therefor, and connections between said striker and trip-lever.

6. In an alarm device, a trip-plate provided with means for attachment to a movable member and provided with a trip, a trip-lever, a pawl yieldingly mounted on the trip-lever and movable lengthwise thereof, an alarm, a striker therefor, and connections between the trip-lever and striker.

7. In an alarm device, in combination with a gong, a swinging striker therefor, means for operating the striker, and an indicator consisting of a case with a slide therein having a stem located in the path of movement of the striker.

8. In an alarm device, a gong, a plural number of striker-arms arranged about the gong, means for operating said arms, and an indicator appurtenant to each arm and including a case with a plate slidably therein having a stem projecting through the case into the path of movement of the striker-arm.

9. In an alarm device, a base with means of attachment to a movable part and having a socket-piece, an arm adjustably mounted in the socket-piece, a trip-plate borne by said arm and having a trip, a trip-lever bearing a pawl to be engaged by the trip, a gong, a striker therefor, and connections between said striker and trip-lever.

10. In an alarm device, a base having means for attachment to a movable part, an arm supported by the base, a trip-plate having a socket-piece adjustably mounted on said arm and bearing a trip, a trip-lever having a pawl located in the path of movement of said trip, a gong, a striker therefor, and connections between said striker and trip-lever.

11. In an alarm device, a base provided with attachment to a movable part and having a socket-piece, an arm adjustably mounted in said socket-piece, a trip-plate having a socket-piece adjustably mounted on said arm and bearing a trip, a trip-lever having a pawl located in the path of movement of said trip, an alarm, a striker therefor, and connections between said striker and trip-lever.

12. In an alarm device, a trip-plate provided with means for attachment to a movable member and having a trip, a trip-lever,

a pawl yieldingly mounted on the trip-lever and movable lengthwise thereof in one direction of movement of the trip but unyielding independently of the lever in the movement 5 of the trip in the opposite direction, a stop for holding the pawl disengaged from the trip, an alarm, a striker therefor, and connections between the trip-lever and striker.

13. In an alarm device, a trip-plate provided with means for attachment to a movable member and provided with a trip, a trip-lever, a pawl yieldingly mounted on the trip-lever and movable lengthwise thereof and

having a limited rotary movement thereon, said pawl yielding to permit movement of the trip in one direction but unyielding, independently of the lever, in the movement of the trip in the opposite direction, means to engage said pawl in its rotative movement to hold it disengaged from the trip, an alarm, a 15 striker therefor, and connections between the trip-lever and striker.
